UNITED STATES PATENT OFFICE.

JOSEPH P. MANTON, OF PROVIDENCE, RHODE ISLAND.

STEERING MECHANISM FOR FERRY-BOATS.

SPECIFICATION forming part of Letters Patent No. 317,817, dated May 12, 1885.

Application filed January 14, 1884. (No model.)

To all whom it may concern:

Be it known that I, JOSEPH P. MANTON, a citizen of the United States, residing at Providence, in the county of Providence and State 5 of Rhode Island, have invented certain new and useful Improvements in Steering Mechanism for Ferry-Boats; and I do hereby declare the following to be a full, clear, and exact description of the invention, such as will enable 10 others skilled in the art to which it appertains to make and use the same, reference being had to the accompanying drawing, and to letters or figures of reference marked thereon, which forms a part of this specification.

15 My invention relates to steering mechanism for ferry-boats or other double-ended vessels provided with two rudders; and it consists, essentially, of a new and novel arrangement of the steering apparatus, whereby the vessel is 20 adapted to be steered from either pilot-house by means of one set of steering-machinery, all as will be more fully hereinafter set forth.

Heretofore in vessels of this class a steering-machine for each rudder has been deemed essential 25 for moving the rudder when actuated by other than manual power.

The object of my invention is to adapt a single steering apparatus by suitable connections, whereby it is susceptible of being readily connected with or disengaged from the rudders, 30 as desired. To this end I have prepared the annexed drawing, which represents a longitudinal vertical section through a portion of a double-ended vessel or ferry-boat provided with 35 two pilot-houses and two steering wheels and drums, and also further showing a power driving mechanism secured to the lower deck and connected, by means of a shaft having wheels mounted thereon, with the steering-drums of 40 each pilot-house. Said drawing further represents means for controlling and operating the reversing mechanism of the engines; also adapted to be worked from each pilot-house.

The following is a description of my invention 45 and the method of operating the same:

H H in the drawing represent the two pilot-houses of an ordinary double-ended vessel, each provided with steering-drums D and steering-wheels D', as common. Upon another or lower deck, w', is located the motive or driving

power, which in this case is represented by engines E, (one back of the other.) The power exerted by said engines is transmitted to the shaft e, and from the latter, by means of a worm, to the worm-wheel G, which is secured 55 to the shaft s. At or near each end of said shaft are secured wheels d', adapted, by means of the belt or rope d', to transmit the power of the engines to the wheels d, secured to the shafts of the steering-drums D, all as fully shown. I 60 do not limit myself, however, to the location and position of the engines or motive power, as shown, as they may be connected at either end of the shaft s, and exterior to the wheels d, or otherwise, without departing from the 65 spirit and intent of my invention. Neither do I limit myself to the use of steam as a motor, as hydraulic, gas, or other engines are as readily adapted to be combined herewith.

f represents a pivoted arm or lever adapted 70 to receive a binding or friction wheel, f', and connect with the belt or rope d'.

Conveniently located within each pilot-house is a hollow standard, A', provided with a trick-wheel, A, each of said wheels being adapted, 75 by means of rods, gear-wheels, &c., to connect with the steering reverse valve, link, or other reversing device which governs and controls the admission of steam to the engines.

R represents the tiller-ropes adapted to connect the drums D and rudder, as common.

The following is the operation: Assuming the steersman to be stationed within the right-hand pilot-house, and the corresponding binder-wheel, f', to be in contact with the rope d', 85 (the opposite binder at the same time being disengaged from the other rope and drum.) The operator now manipulates the trick-wheel A, which by means of suitable connections conveys motion to the reversing-valve, link, or other valve-gear of the engine, thereby admitting steam into the latter, which, by means of gearing, G, &c., causes the main shaft s to revolve, the power therefrom being transmitted to the drums D through the medium of the 90 wheels d' d and rope d', as before described, thus turning the drum in the desired direction. The reverse of the foregoing movements causes the drum to revolve in a contrary direction.

It is obvious that the steering can be effect- 100

ed from the other or left-hand pilot-house, when the vessel is to sail in the opposite direction, by means of its wheel A, &c., therein, as fully shown.

5 I prefer to connect the trick-wheel A so that one turn thereof to port or starboard gives a corresponding turn, port or starboard, to the steering-drums D.

10 My invention does not preclude the use of compass, indicator for showing the vibration of the rudder, or any other accessory as commonly employed.

15 Having thus described my invention, what I claim as new, and desire to secure by Letters Patent, is—

20 1. In a steamboat having two rudders and two steering-drums, the engine E, or other suitable driving motor connecting said drums, by means of the gear G, shaft s, &c., substantially as described, in combination with the binding or friction wheels f', each mounted upon a swinging lever, f, and suitable means for operating the same, whereby said drums are adapted to be connected to or disconnected from 25 the driving mechanism, substantially as herein shown and set forth.

2. In a double-ended vessel or ferry-boat having a steering-wheel and drum at each end thereof, the combination therewith of the driving means herein described, consisting of engines E, gearing G, shaft s, carrying said gear, and

two wheels, d', adapted to drive the steering-drums, substantially as shown and set forth.

3. In a double-ended vessel or ferry-boat having a steering-wheel and drum at each end thereof, and means, substantially as shown and described, for operating the same, consisting of the motor E, gearing G, shaft s, wheels d' d, &c., the combination therewith of the trick-wheels A, suitably mounted and connected 40 by means of gearing a a² to the vertical shaft a³, which operates a suitable reversing-valve, as and for the purpose set forth.

4. In a vessel having two pilot-houses, each provided with the steering-wheel D', drum D, wheel d, and trick-wheel A, the combination therewith of engines E, connected by gearing t, the longitudinal shaft s, the latter adapted by means of wheels d' and belts d² to transmit power from the engine to the steering-drums, 45 a device for frictionally engaging with said belts, a reversing-gear connected by suitable means whereby the steersman in turning the trick-wheel A controls the movement of the engines and drums, all constructed to operate as 50 and for the purpose herein shown and set forth.

In testimony whereof I have affixed my signature in presence of two witnesses.

JOS. P. MANTON.
